S. CONDON

BENCH VISE

Filed Feb. 27, 1922

FIG. 5

FIG. 4

FIG. 1

FIG. 2

FIG. 3

INVENTOR.
Stephen Condon.

Milton S. Corrall,
ATTORNEY

UNITED STATES PATENT OFFICE.

STEPHEN CONDON, OF SPENCER, IOWA.

BENCH VISE.

Application filed February 27, 1922. Serial No. 539,616.

To all whom it may concern:

Be it known that I, STEPHEN CONDON, a citizen of the United States, and a resident of Spencer, in the county of Clay and 5 State of Iowa, have invented certain new and useful Improvements in Bench Vises, of which the following is a specification.

My invention aims primarily to provide an improved device to supplant the usual 10 carpenters' bench hook for holding boards while they are being planed.

A further object of the invention is the production of a vise mechanism adapted to hold boards securely against lateral or 15 longitudinal movement while they are being planed or otherwise worked upon.

Still another object of the invention is the production of a device of this sort which is instantly adjustable to suit the work.

20 The invention has for a further object the production of an improved carpenters' vise adapted to hold work securely on top of the bench or which may be employed to hold the work firmly against the face or 25 side of the bench.

With these and numerous other objects in view, the invention, consisting in the construction, combination and novel arrangement of parts, will be clearly understood 30 from the following description, reference being had to the accompanying drawings which form a part of this application and in which like figures of reference indicate corresponding parts throughout the several 35 views, of which,—

Fig. 1 is a plan of a device constructed in accordance with my invention and mounted on the end of a bench, parts being cut away and shown in section.

40 Fig. 2 is a side elevation of the same.

Fig. 3 is a vertical section of the same taken on the line 3 of Fig. 1.

Fig. 4 is an end elevation of one of the vise jaws, and

45 Fig. 5 is a fragmentary, vertical section similar to Fig. 3 of a modification of the mounting of one of the jaws.

While I have illustrated and hereinafter described the preferred embodiment of the 50 invention, I would not be understood as being limited to such specific construction, for various alterations and modifications may be made in the details of construction and arrangement of parts herein disclosed 55 without departing from the spirit and

scope of the invention as defined in the appended claims.

The preferred form of my device is particularly designed for mounting upon and use with the combination bench and trestle 60 forming the subject of my co-pending application No. 539,615, filed February 27, 1922; yet it is equally as well adapted for mounting upon the usual carpenter's bench or any other suitable support.

65 Referring, now, to the illustrations, 6 represents the end portion of a plank of a carpenter's bench or other suitable support. The main supporting body of my device preferably consists of an elongated 70 block, 7, extending transversely across and abutting the end of the member, 6. On the under side of the body, 7, is a cleat, 8, suitably secured to the body, 7, as by bolts, 9, or otherwise. The cleat, 8, extends below 75 and is secured to the member, 6, as by bolts, 10, or otherwise, and the front edge of the body is clad with a metal strip, 11, suitably secured to the body, 7, as by screws, 12, or otherwise, the said strip, 11, being extended 80 to embrace the edge of the member, 6, to which it is suitably secured by screws, 13, or otherwise. The body, 7, is so constructed and mounted that its upper side is flush with the upper side of the member, 6.

85 I provide adjacent the face of the block a screw-controlled vise-jaw, preferably comprising a rectangular plate, 14, through which passes a bolt, 15, projecting into an opening, 16, in the body, 7, and threaded 90 into a block, 17, embedded in the body. To the outer end of the bolt, 15, is fixed a T-head, 18, carrying the usual vise-operating handle-bar, 19. The portion of the bolt, 15, passing through the jaw, 14, is reduced 95 to provide a shoulder, 20, engaging the inner face of the jaw. The said jaw carries a pin, 21, which reciprocates freely in an opening, 22, in the body, 7; and serves to prevent rotary movement of the jaw. The jaw 100 extends a distance above the body, the said extended portion being provided with a projection, 23, which serves as a stop for boards or other work, as will be presently made more clear.

105 The jaw, 14, co-acts with a second jaw which is carried by suitable means to slide towards its companion, and so constructed and mounted that it is secure against accidental displacement when placed in co-op- 110

erative relation with its companion. The said second jaw may comprise a bar, 24, extending transversely across the body, 7, disposed longitudinally with respect to the bench and having its engaging face in substantial parallelism with the face of the jaw, 14. The said second jaw overhangs the free edge of the body, 7, and is provided with a channel, 25, slidable on a guide-bar, 26, preferably rectangular in cross section and carried between an extended portion, 27, of the cleat, 11, and an arm, 28, on the opposite end of the body, 7. The said second jaw is also provided with a shoulder, 29, positioned below the guide-bar, 26, to slidably engage the under side of the bar, 26, adjacent the side edge of the bar remote from the body to prevent vertical movement of the channeled end of the jaw, the vertical movement of its free end being prevented by a shoulder, 30, on the jaw slidably engaging the under side of a metal guide strip, 31, secured to and overhanging the edge of the body, 7, (Fig. 3).

I have illustrated the operation of the device by indicating in dotted lines a board, 32, resting upon the bench and having its end portion disposed between the jaws and abutted against the stop, 23, whereby it will be seen that by turning the screw, 15, in the appropriate direction the end portion of the board will be clamped firmly between the jaws, lateral movement of the jaw, 24 being prevented by its binding on the guide-bar, 26. Thus it will be seen the board is held firmly against either longitudinal or lateral movement while it is being dressed. It is evident the jaw, 24, may be instantly adjusted laterally by grasping its channeled end portion and sliding it in either direction on the bar, 26, and it is also apparent that it can not be moved by lateral pressure on its free end portion. To oppose any tendency of the bar, 26, to buckle under strain of the jaw, 24, I reembrace its intermediate portion by extending the cleat, 8, and securing it to the under side of the bar, 26, as by a machine screw, 33, or otherwise. It is also apparent that when desired boards or other work may be clamped firmly against the face of the bench by securing such work between the jaw, 14, and the cleat, 11. By mounting the jaw as shown in Fig. 5, the guide member, 31, may be dispensed with. In this construction the bar, 26, is made relatively wider than is shown in the previously described form, and the jaw, 24, is provided with a T-groove, 34, to slidably support the jaw in the bar.

Having thus described my invention, what I claim as new and desire to secure by Letters Patent of the United States, is:

1. A device of the class described including a horizontal body, a screw-controlled vise jaw movable toward and from the side thereof, and projecting above the plane thereof, a transverse guide bar spaced from the end of the body, and an elongated second jaw slidably supported on the bar and projecting over the surface of the body. 65

2. A device of the class described comprising a horizontal body, a screw-controlled vise jaw movable toward and from the side thereof and projecting above the plane 75 thereof, a transverse guide bar spaced from the end of the body, and an elongated second jaw projecting over the surface of the body and having one end portion slidably mounted on the bar, said second jaw being 80 adapted to grip the bar to prevent sliding when lateral pressure is applied to its projecting portion.

3. A device of the class described including a horizontal body, a screw-controlled 85 vise jaw movable toward and from the side thereof and projecting above the plane thereof, a transverse guide bar spaced from the end of the body and disposed below the plane of the surface thereof, an elongated 90 second jaw having one end portion above the surface of the body and its other end portion slotted to slide upon the guide bar, a transverse strip on the body having one edge portion overhanging the end of the 95 body, and a shoulder on said second jaw slidably engaging the under side of the overhanging edge portion of said strip.

4. A device of the class described including a horizontal body, a screw-controlled 100 vise jaw movable toward and from the side thereof and projecting above the plane thereof, a transverse guide bar spaced from the end of the body and disposed below the plane of the surface thereof, an elongated second jaw having one end portion above the surface of the body and its other end portion channeled transversely on its under side to slide on the bar, a shoulder 105 on the said channeled end portion slidably engaging the under side of the bar, a transverse strip on the body having one edge portion overhanging the end of the body, and a shoulder on the said second jaw slidably engaging the under side of the overhanging edge portion of said strip. 110

In testimony whereof, I have hereunto set my hand this 11th day of February, 1922.

STEPHEN CONDON.
